UNITED STATES PATENT OFFICE.

PAUL CRICCHIO, OF NEW YORK, N. Y., ASSIGNOR TO MAJESTIC LAMP WORKS, OF NEW YORK, N. Y., A PARTNERSHIP CONSISTING OF PHILIP SILBERHARTZ, JACOB SILBERHARTZ, AND HARRY SCHEINER, ALL OF BROOKLYN, NEW YORK.

DESIGN FOR A BASE FOR CLOCK CASES OR ARTICLES OF ANALOGOUS NATURE.

Application filed April 24, 1929. Serial No. 30,997. Term of patent $2\frac{1}{2}$ years.

To all whom it may concern:

Be it known that I, PAUL CRICCHIO, a citizen of the United States, and a resident of New York, county of Bronx, and State of New York, have invented a new, original, and ornamental Design for a Base for Clock Cases or Articles of Analogous Nature, of which the following is a specification, reference being had to the drawing, forming a part hereof,

In the drawing:

Figure 1 is a perspective view of the base for clock cases or articles of analogous nature; and

Figure 2 is an end view of the same.

I claim:

The ornamental design for a base for clock cases or articles of analogous nature substantially as shown.

PAUL CRICCHIO.
